Primary Examiner — Gino Colan

(57) **CLAIM**

The ornamental design for a garden edging connector, as shown and described.

DESCRIPTION

FIG. 1 is a front isometric view of a garden edging connector showing my new design, a rear isometric view being a mirror image thereof;

FIG. 2 is a right side view of the garden edging connector, a left side view being a mirror image thereof; and,

FIG. 3 is a rear view of the garden edging connector.

1 Claim, 2 Drawing Sheets**FIG. 1**

FIG. 2

FIG. 3
